PROCESS AND APPARATUS FOR FUME CONTROL.

Application filed October 15, 1921. Serial No. 508,031.

To all whom it may concern:

Be it known that we, ROBERT S. PERRY and PAUL W. WEBSTER, citizens of the United States, residing, respectively, in New York city, county of New York, borough of Manhattan, and State of New York, and Pelham Manor, county of Westchester, and State of New York, have invented certain new and useful Improvements in Processes and Apparatus for Fume Control, of which the following is a full, clear, and exact specification.

Our invention relates to the shielding, control and removal of fumes and devices suitable for the application of our process and refers particularly to the shielding, control and removal of fumes arising from heated organic matters and apparatus relating thereto.

In many industries, including the production of paint vehicles, varnishes and similar products, it is necessary to heat oils, gums, and materials containing the same and other similar constituents, to a temperature at which the constituents and ingredients, or volatile products therefrom, will be converted into fumes, and, the removal of these fumes from the heated container and away from contact with the distillate residuum therein is an essential feature of the process.

While the constituents thus recovered into fumes are frequently objectionable ingredients of the distillate residuum from which they are recovered in process of production, yet they are frequently of great value for other purposes, and hence, their condensation or collection, under conditions which will either conserve the values thereof as evolved, or will enhance the values thereof, either or both, as products and as created products, or recovered, or reclaimed, materials is highly advisable and desirable.

If the heating of the oils and gums, or oil or gum carrying bodies, is conducted in open vessels, it is evident that the valuable fume material evolved cannot be recovered but constitute considerable losses and economic wastage.

The desired temperature obtained in the materials thus heat treated is usually obtained by exterior heating of the walls of the containing apparatus, or by heating coils therein, frequently to a much higher

temperature, as for instance in the exterior heating of a varnish kettle. 55

It is well known and established that in the treatment of oils, gums, materials containing the same and other similar constituents by heat to evolve and remove distillates as fume therefrom, that such fume 60 consists of mixtures of fixed or saturated gaseous compounds, which are non-decomposable and stable gases within the upper limits of temperature applied as above mentioned, or otherwise, together with non-fixed 65 or un-saturated gaseous compounds, which in time upon exposure to and within the upper limit of the said applied temperature will decompose into other and more stable bodies. 70

The temperatures at which these decompositions may take place at about atmospheric pressure, and the time interval in which they take place at such pressure and upon exposure to such temperatures, may 75 be herein identified respectively as "secondary decomposition temperature" and "time requirement for secondary decomposition" and the temperature at which any entire fume is evolved from the original materials of the charge at about atmospheric pressure may be herein identified as the "distillation temperature".

These components of the fume which are the more valued and useful in industry are 85 generally those with lower secondary decomposition temperature when compared with other components of a given fume; both of which may be identified as the unstable and the stable fraction or fractions respectively. 90

Again, many of the components of such fumes are reactive with the materials of the container surfaces at about the temperature of distillation and at about normal pressures. 95

In all the prior art of distillation the conservation of distillates and of unstable fractions of a fume, has been accomplished by reducing the gas pressure and thus dropping the temperature of formation of distillate or by hastening the removal of the gas from the zone of heat treatment, either or both, as in vacuum apparatus and as in closed retorts and kettles which have suction fan or pressure blower attachment. 100

In the heat treatments of the materials

under consideration, the fumes given off at the distillation temperature for the fumes, with few if any exceptions, contain the more valuable components in the form of unstable fractions at the temperatures of the heating walls of the containing apparatus or of the heating coils therein, and in all the prior art there has been secondary decomposition of these unstable fractions with serious losses in their production, due to the high temperature of the heated walls or coils.

In all the prior art of distilling there has never been any practice or suggestion of conserving these unstable fractions from the temperatures of their secondary decompositions, as present in the walls of the containing apparatus, by means of shielding layers of stable gas, which may move freely between the fume as distilled and the higher temperature walls of the container and which because moving freely, may efficiently convey heat from such heating walls to the interior of the container, and which at the same time further act as shielding layers of stable gas to prevent reaction between components of the fume and the heated container surfaces, resulting in the decomposition of at least a portion of the fumes or the disintegration of the walls, or both.

The process of the invention of this application is designed to accomplish any and all of these most desirable improvements and to thus conserve fume values and protect the same from the destructive temperatures of the surfaces of the container, and to protect them and also the container itself from their interaction, and to attain further most desirable protections as of fire risk.

As an example, the fumes volatilized in heating gums and oils in the manufacturing of varnish have great fire risks and explosive properties when mixed with considerable quantities of air, the proportion of such fire, or explosive, producing mixture varying with the particular character of the fumes.

It is strongly advisable, therefore, that the production of such dangerous mixtures be avoided by preventing such an admixture of the fumes and air as will make possible fire or explosion.

It is evident that such a control of the mixture of fumes and air is impossible when open vessels are employed, as fumes arising therefrom, being heavier than air, flow downwardly over the sides of the vessel, become mixed with air in varying proportions and very frequently in actual practice become ignited, or explosive, through the action of the fire beneath the vessel.

It has been the practice, therefore, to employ vessels, or kettles covered with a lid,

or cover, having a vent, or opening, therein to allow of the escape of the fumes.

The employment of such vented cover, while it has reduced the fire and explosive danger to a small degree, has not entirely, or even approximately, removed this danger, as the fumes escaping from the vent are still allowed to become mixed with varying quantities of air, thus producing fire and explosive mixtures.

These vented covers have introduced additional disadvantages and objectionable features to the process that were not incident to the open kettles. The fumes contacting with the higher temperatures of the kettle walls suffer secondary decomposition into less volatile products which are dark and of inferior quality and these products running down the kettle walls, or mixed in the fume or contacting with the cooler cover are partially, or all, condensed, falling back into the melt, thus impairing the quality and cooling the latter and requiring additional time and heat to again volatilize them. Fumes of this kind, being frequently of an acid character, have a corrosive effect upon metallic surfaces of the kettle walls and cover, and hence carry a coloration back into the charge, which is most objectionable, especially in the production of light colored paint vehicles and varnishes.

Further, it is evident that, as these vapors are heavier than air, they will escape through the vent only as they are forced therethrough by the vapor density of the production fumes within the kettle, thus causing an increased vapor pressure upon the melt and, with the employment of an increased amount of heat units necessary for the following out of the process, and with a corresponding raise of temperature of operation, and darkening and impairment of the product from decomposition of unstable fractions of the fume at such higher temperatures, and impairment of quality and value of fume products.

From the above it will be seen that a process which would overcome the fire risk and the explosion risk, prevent reaction between, or due to, the fume and the heated surfaces of the container, with its consequent injury to the quality of the products, solid and gaseous, and prevent the return of condensed or decomposed products from fume to the charge, and prevent the necessity of vapor pressure-removal of the fumes, would be a very considerable advance over the described methods of production and would have great commercial value.

The process of our invention and the device suitable for carrying out said process, produce all of these, and other valuable results and present a method and device for the heat treatment of oils, gums and mate-

rials containing the same, etc., with enhanced economic and practical results and applications.

We have discovered that if air, or other desirable gas, be admitted into the container under proper conditions and a proper artificial pressure or suction, as an introduction means, be employed, that the production fume can all, or in part, be effectively removed from the container without their return by condensation to the charge and without reactive effect upon the surfaces of the container and with protection against the secondary decomposition of unstable portions of the fume, and with avoidance of the danger of fire and explosion.

The effect of the produced current of air, or gas, is to form a moving blanket and shield of gas over the interior of the face of the container between the fume and the container surfaces. The small portion of the fumes which penetrates this air, or gas, blanket, is sucked up to the outlet with the blanket and diffused and diluted in the blanket. In the example above given of varnish kettle practice, the blanket may be of air, or gas, of a suitable temperature to protect the unstable gases from secondary decomposition and all of the fume from condensation.

Again, in the example given of varnish kettle practice of manufacture, if the gas introduced to serve as a blanket and shield be a gas non-combustible with the fume and be fixed and stable at the temperature used, such as carbonic acid gas, protection is afforded against the risk of combustion and consequent loss of fume and the risk of fire and explosion can be eliminated, together with protection against oxidation and consequent improvement of the quality of the fume over that which would ensue if the fume were exposed to the oxygen of air.

Again, in the example given of varnish kettle practice of manufacture, the moving blanket of air or gas may be so introduced that it also carries the fumes with it, as exemplified in the drawings herewith, thus causing their uniform removal from the vessel and preventing their being "pocketed," decomposed by heat and reacted upon in the upper portion of the kettle in the proximity of the walls and of the cover.

The gas introduced as a blanket or shield may be heated with great advantage in many distillation processes, as for example varnish melts, to help to so maintain the temperature of the fume as to protect the fume against condensation within the container and consequent addition of condensed fume products to the distillation residuum, which has heretofore frequently resulted in products of impaired quality and color.

While we have given as an example of the

application of the process of our invention, 65 the application thereof to the heat treatment of gums and oils, in a varnish kettle and to the design and equipment of said kettle container, we do not wish to be understood to confine ourselves thereto, but our 70 process is applicable to many other distillations and to the design of the containers and equipment incidental thereto for such distillations.

Again in the example given of varnish 75 kettle practice of manufacture, we have further found that the artificial removal of the fumes can be so governed and controlled as to prevent the possibility of the formation of inflammable, or explosive, mixtures with 80 air, and that it can also be so governed as to control the rapidity of the removal of the fumes from the kettle to the point of greatest efficiency.

As described above, and claimed, the process 85 of our invention is applicable to many industries in which fumes are evolved, and as an example we will describe our method of applying it to the fumes evolved in the manufacture of varnish.

In the accompanying drawings, illustrating 90 one form of a device suitable for the carrying out of the process of our invention, similar parts are designated by similar numerals.

Figure 1 is a diagrammatical vertical cross-section of one form of a device in which our process may be followed.

Figure 2 is a section through the line 2—2 of Figure 1.

Figure 3 is a broken section through the gas-feed pipe illustrating the direction of the gas issuing therefrom.

In the accompanying drawings, the single kettle section of the melting room comprises 105 the two side walls 10, 10 and the floor 11, the latter having the depressed fire-box 12, in which are the grate-bars 13 for carrying coal, or coke, 14 for combustion.

The melting kettle comprises the bottom 110 15 and the annular side 16, the kettle being carried by the wheels 17, 17. A removable cover 18 is placeable upon the kettle and has a flue 19, connected with a source of suction, not shown, and an opening 20, for purposes 115 described later.

Suspended from a plurality of hooks 21, 21 within the kettle by means of a plurality of chains 22, 22 is a manifold pipe 23, which in turn is connected to the gas feed pipe 24 120 by a series of pipes 25, 25. The manifold 23 carries the pipe 26, passing through the opening 20 of the cover 18, the outer extremity of the pipe 26 being connected to the flexible pipe 27, which in turn is connected with a source of gas supply, not shown.

The gas pipe 24 has a plurality of

upwardly and outwardly directed holes, or perforations, 28, 28 and a plurality of downwardly and outwardly directed holes, or perforations, 29, 29.

5 The device contains a collapsible, or removable, combustion chamber cover 30, the details of which are not shown as they are not essential elements in the process of our invention.

10 The carrying out of the process of our invention in the described device is as follows:

The ingredients 31 necessary in the production of the desired varnish are introduced into the kettle, and the manifold 23 and the gas-feed pipe 24 are suspended above the ingredients at the desired distance by means of the chains 22, 22 and the hooks 21, 21. The cover 18 is then placed upon the kettle and the kettle wheeled over the fire 14, and the collapsible chamber cover 30 placed into position in order that the combustion-gases will pass through a combustion flue, not shown, instead of passing up and over the kettle cover. The pipe 19 is then connected to a source of draught, or suction, and the pipe 27 is connected to a source of desired gas, which, for purposes of example may be assumed to be carbon dioxide.

30 During the evolution of the fumes from the heated varnish mixture and their withdrawal from the kettle through the conduit 19, the cooler carbon dioxide gas is forced into the gas-feed pipe 24 and outwardly through the plurality openings 28, 28, 29, 29, and as the gas will also be drawn upwardly, it will form a moving blanket, or shield, of cooler gas between the evolved fumes and the heated side of the kettle above the ingredient mixture, thus preventing the fumes from reaching the secondary decomposition temperature, with its resultant changes, in the composition of the evolved fumes.

Attention is called to another valuable 45 feature of our process. In the present employed processes it is necessary that the heat of combustion be not allowed to impinge upon the side of the kettle above the ingredients on account of the secondary decomposition of the evolved fumes due to their contact with this highly heated surface and for that reason, the chamber cover should be situated below the surface of the ingredients as shown by the dotted lines 30'. It is evident, therefore, that the cooler kettle sides above the ingredients will cause some of the fume contents to be condensed and returned to the kettle, thus causing the necessity of additional heat units and time to re-evolve 55 them.

In our process, however, the introduced gas, forming the moving blanket may be heated to such a temperature as to prevent both the condensation and secondary decomposition of the evolved fume contents.

Another advantageous feature of our process is that the gas blanket may be formed from a gas which is inert to the evolved fumes, and which will not form an explosive or combustible mixture therewith in any proportions, thus enveloping the fumes and removing them from all danger of fire or explosion.

Other advantages of the process of our invention will be evident upon a consideration of its wide application and the extensive field of changes that may be made in the quality and quantity of introduced gas, the temperatures employed and its other elements in order to meet the requirements of any particular process of manufacture in which secondary decomposition, over-heating, condensation, fire danger and explosion danger are to be avoided.

We do not limit ourselves to the particular size, shape, number or arrangement of parts, nor to the particular products, steps of procedure or modes of operation as shown and described, all of which may be varied without going beyond the scope of our invention as described, shown and claimed.

What we claim is:

1. The process of controlling heated fumes within a receptacle which comprises introducing an inert gas into the receptacle, causing it to form a layer between the fumes and the walls of the receptacle, maintaining the inert gas at a temperature below that of the receptacle walls and removing the fumes from the receptacle while maintaining a gas layer between the fumes and the walls of the receptacle.

2. The process of controlling heated fumes within a receptacle which comprises introducing an inert gas below the temperature of the fumes into the receptacle, causing it to form a layer between the fumes and the walls of the receptacle, maintaining the inert gas at a temperature below that of the receptacle walls and removing the fumes from the receptacle while maintaining a gas layer between the fumes and the walls of the receptacle.

3. In the treatment of heated fumes within a receptacle, the step which comprises introducing a blanket of inert gas between the fumes and the heated sides of the receptacle, the temperature of the gas being lower than that of the fumes.

4. In the heat treatment of fume producing materials within a receptacle in which the fume products are affected by contact with the heated walls of the receptacle, the step which comprises introducing a blanket of inert gas between the fumes and the heated walls.

5. In the heat treatment of fume producing materials within a receptacle in which the fume products are affected by contact

with the heated walls of the receptacle, the step which comprises introducing a blanket of inert gas between the fumes and the heated walls, maintaining the gas below the temperature of the heated walls.

6. The process of controlling heated fumes within a receptacle which comprises introducing a heated inert gas into the receptacle, causing it to form a layer between the fumes and the walls of the receptacle, and removing the fumes from the receptacle while maintaining a gas layer between the fumes and the walls of the receptacle.

7. The process of controlling heated fumes within a receptacle which comprises introducing into the receptacle a gas heated below the temperature of the walls of the receptacle and above the condensing temperature of the fumes, forming the introduced gas into a blanket between the fumes and the walls of the receptacle and removing the gas and the fumes from the receptacle while maintaining the gas blanket.

8. The process of controlling fumes evolved during their production which comprises heating the fume producing ingredients within a receptacle, introducing heated inert gas into the receptacle, causing the gas to form a layer between the fumes and the

walls of the receptacle and removing the gas and fumes from the receptacle while maintaining a moving gas layer between the fumes and the walls of the receptacle.

9. The process of controlling fumes evolved during their production which comprises heating the fume producing ingredients within a receptacle, introducing into the receptacle an inert gas heated below the temperature of the walls of the receptacle and above the condensing temperature of the evolved fumes, forming the gas into a blanket between the fumes and the walls of the receptacle, and removing the fumes and the gas from the receptacle while maintaining a moving blanket of gas between the fumes and the walls of the receptacle.

10. In a device for controlling fumes, an enclosing receptacle, a conduit connecting the receptacle with a suction means and means whereby a gas may be introduced into the receptacle to form a gas blanket around the inner faces of the receptacle walls.

Signed at 31 Union Square W. in the county of New York and State of New York this 13th day of October, 1921.

ROBERT S. PERRY.
PAUL W. WEBSTER.
